UNITED STATES PATENT OFFICE

151,310

DESIGN FOR A VEHICLE HOOD ORNAMENT
OR SIMILAR ARTICLE

Howard F. Yaeger, Detroit, Mich., assignor to Packard Motor Car Company, Detroit, Mich., a corporation of Michigan

Application May 14, 1947, Serial No. 139,044

Term of patent 14 years

(Cl. D14—18)

To all whom it may concern:

Be it known that I, Howard F. Yaeger, a citizen of the United States, residing at Detroit, county of Wayne, State of Michigan, have invented a new, original, and ornamental Design for a Vehicle Hood Ornament or Similar Article, of which the following is a specification, reference being had to the accompanying drawing, forming a part thereof.

I claim:

The ornamental design of a vehicle hood ornament or similar article, substantially as shown.

HOWARD F. YAEGER.
